UNITED STATES PATENT OFFICE

JAMES G. BLUNT, OF SCHENECTADY, NEW YORK

CROSSTIE STRUCTURE FOR LOCOMOTIVE SIDE FRAMES

Application filed September 6, 1929. Serial No. 390,697.

This invention relates to improvements in cross-tie structures for locomotive side frames, and more particularly to cross-tie structures designed for application between the front ends of the side frame members of a locomotive.

An object of the invention is to provide a cross-tie structure which is economical to manufacture and maintain; which is convenient to install and remove; which is of great durability; which is adapted to firmly and securely connect together the side frame members, the cylinder saddle, and the bumper beam; and which embodies a novel, rugged, and efficient center pin construction.

Another object of the invention is to provide a cross-tie structure, embodying the advantages indicated, which may be formed as an integral or one piece casting.

Other objects of the invention will hereinafter readily appear.

The improvement claimed is hereinafter fully set forth.

In the accompanying drawing: Figure 1 is a top plan view of a cross-tie construction embodying the invention; Fig. 2, a side elevation thereof; Fig. 3, a longitudinal, vertical section on the line III—III of Fig. 1; Fig. 4, a partial front end view, in elevation; Fig. 5, a partial, rear end view, in elevation; Fig. 6, a vertical transverse section, taken on the line VI—VI of Fig. 1; Fig. 7, a vertical, transverse section, taken on the line VII—VII of Fig. 1; and, Fig. 8, a partial, horizontal, transverse section taken on the line VIII—VIII of Fig. 2.

In the practice of the invention, referring descriptively to the specific embodiment thereof which has been selected for exemplification herein, the cross-tie structure comprises an intermediate, or cylinder saddle supporting portion, A, a front portion, B, extending forwardly of the cylinder saddle portion, and a rear portion, C, extending rearwardly of the cylinder saddle portion.

The structure embodies two substantially parallel vertical side walls, 10, each having front and rear portions, 10^a, and 10^b disposed in substantially the same vertical plane and extending respectively throughout the lengths

of the front and rear portions, B and C, and an intermediate portion, 10^c, set inwardly of the front and rear portions, at the saddle supporting portion, A, of the cross-tie structure, to provide clearance for the heads of the usual bolts by which cylinder castings are attached to side frame members. Suitable bolt holes, 10^d, are provided in the front and rear portions of the side walls for bolting the cross tie structure to the side frame members. Each rear portion, 10^b, of the side walls is formed at its rear end with a vertical upstanding extension, 10^e, to provide additional area for bolting to side frame members.

The rear portions, 10^b, of the side walls are tied together by a single transverse web, 11, which has a longitudinal portion, 11^a, joined to the tops of the rear portions of the side walls and bellied upwardly therefrom to provide clearance for a truck accessory, and a vertical or upstanding portion, 11^b, joined to the front of the extensions, 10^e.

The intermediate and front portions, 10^c and 10^a, of the side walls are tied together by two vertically spaced webs, 12 and 13, the web, 12, being joined to the tops of such portions, and the web, 13, to the bottoms thereof. The top web, 12, projects laterally beyond the intermediate portion, 10^c, of each side wall to provide a reinforcing flange, 12^a. A portion of the sides of both webs, at the forward ends thereof, terminate short of the side walls, and are joined together by vertical walls, 14, which in turn are joined to the front portions of the side walls by horizontal webs, 15^a, disposed intermediate their heights. This construction enables the bolts for fastening the cross-tie structure to the side members of the frame, to be conveniently applied.

The webs, 12 and 13, and the front portions, 10^a, of the side walls are joined to a transverse vertical bumper flange or bracket, 16.

The top web, 12, at the cylinder saddle portion of the cross-tie structure, is formed with four spaced bosses, 17, for the attachment of suitable cylinder saddles.

To provide for a center pin, the top and the bottom webs, 12 and 13, are each formed with a circular aperture and are connected by a cylindrical wall, 18, which forms a socket,

18^a, for the reception of the cylindrical extension, 19^a, of a center pin, 19. The center pin is formed with circumferential segmental flanges, 19^b, having their top faces formed with bosses, 19^c, which fit in grooves, 13^a, in the bottom face of the bottom web, 13. Bolts, 19^d, passing through the bossed portions of the flange, 19^b, of the center pin, and the bottom walls of the grooves, 13^a, in the bottom web, in cooperation with the cylindrical extension, 19^a, of the center pin and its socket, 18^a, serve to firmly attach the center pin to the cross tie structure.

Suitable ribs, 18^b, radiating from the socket wall, 18, and connecting the top and the bottom webs serve to reinforce the structure to efficiently withstand the stresses imposed on the center pin.

The bottom web, 13, is connected at its rear to an upstanding wall, 21, which in turn is connected to the top web, 12. The wall, 21, has a bellied portion, 21^a, to afford clearance for a truck accessory.

The invention contemplates forming the entire cross-tie structure, exclusive of the center pin, as an integral or one-piece casting; and also forming the entire cross-tie structure together with a center pin as an integral or one-piece casting.

While one of the preferred forms of construction has been described and shown, it is obvious that many variations in procedure, and in the form, arrangement, and construction of the parts, may be resorted to, and the invention, therefore, is not limited to the particular embodiment disclosed, but includes such changes and modifications as come within the spirit and scope of the invention as set forth in the appended claims.

The invention claimed and desired to be secured by Letters Patent is:

1. In a cross-tie structure for connecting the front ends of locomotive side frame members, the combination, in an integral casting, of vertical side walls adapted to tie together a pair of side frame members, and vertically spaced transverse webs connecting the walls, the upper of the webs being adapted to support a cylinder saddle.

2. In a cross-tie structure for connecting the front ends of locomotive side frame members, the combination of a cylinder saddle supporting portion, and a front portion projecting forwardly thereof adapted to tie together a pair of side frame members, the cylinder saddle supporting portion comprising vertically spaced transverse webs.

3. In a cross-tie structure for connecting the front ends of locomotive side frame members, the combination, in an integral casting, of a portion adapted to support a cylinder saddle, and a front portion projecting forwardly thereof adapted to tie together a pair of side frame members, the cylinder saddle supporting portion comprising vertically spaced transverse webs.

4. In a cross-tie structure for connecting the front ends of locomotive side frame members, the combination, in an integral casting, of a cylinder saddle supporting portion, and a rear portion projecting rearwardly thereof adapted to tie together a pair of side frame members, the cylinder saddle supporting portion comprising vertically spaced transverse webs.

5. In a cross-tie structure for connecting the front ends of locomotive side frame members, the combination of a front portion, a rear portion, both portions being adapted to tie together a pair of side frame members, and a cylinder saddle supporting portion disposed intermediate the front and rear portions and comprising vertically spaced transverse webs. 75

6. In a cross-tie structure for connecting the front ends of locomotive side frame members, the combination, in an integral casting, of a front portion, a rear portion, both portions being adapted to tie together a pair of side frame members, and a cylinder saddle supporting portion disposed intermediate the front and rear portions and comprising vertically spaced transverse webs. 80

7. In a cross-tie structure for connecting the front ends of locomotive side frame members, the combination, in an integral casting, of a front portion, a rear portion, both portions being adapted to tie together a pair of side frame members, and a cylinder saddle supporting portion disposed intermediate the front and rear portions and comprising vertically spaced transverse webs. 85

8. In a cross-tie structure for connecting the front ends of locomotive side frame members, the combination, in an integral casting, of a front portion, a rear portion, both portions being adapted to tie together a pair of side frame members, and a cylinder saddle supporting portion disposed intermediate the front and rear portions, the intermediate and front portions each comprising vertically spaced transverse webs. 95

9. In a cross-tie structure for connecting the front ends of locomotive side frame members, the combination, in an integral casting, of a front portion, a rear portion, both portions being adapted to tie together a pair of side frame members, and a cylinder saddle supporting portion disposed intermediate the front and rear portions, the intermediate and front portions each comprising vertically spaced transverse webs. 105

10. In a cross-tie structure for connecting the front ends of locomotive side frame members, the combination, in an integral casting, of a cylinder saddle supporting portion embodying vertically spaced transverse webs, a front portion projecting forwardly of the saddle supporting portion and adapted to tie together a pair of side frame members, and a bumper beam bracket at the forward end of the front portion. 115

11. In a cross-tie structure for connecting the front ends of locomotive side frame members, the combination, in an integral casting, of a front portion, a rear portion, both portions being adapted to tie together a pair of side frame members, a cylinder saddle supporting portion disposed intermediate the front and rear portions and comprising verti- 125

cally spaced transverse webs, and a bumper beam bracket at the forward end of the front section.

11. In a cross-tie structure for connecting the front ends of locomotive side frame members, the combination of a portion for supporting a cylinder saddle, and a front portion projecting forwardly thereof adapted to tie together a pair of side frame members, the saddle supporting portion comprising vertically spaced transverse webs and a socket for a center pin stem.

12. In a cross-tie structure for connecting the front ends of locomotive side frame members, the combination, in an integral casting, of a portion for supporting a cylinder saddle, and a front portion projecting forwardly thereof adapted to tie together a pair of side frame members, the saddle supporting portion comprising vertically spaced webs and a socket for a center pin stem, the walls of the socket joining the webs.

13. In a cross-tie structure for connecting the front ends of locomotive side frame members, the combination of a portion for supporting a cylinder saddle, said portion comprising side walls and vertically spaced transverse webs connecting the side walls, and a rear portion projecting rearwardly of the saddle supporting portion and comprising a pair of vertical side walls each having a vertical extension affording increased area for attachment to side frame members, and a longitudinal transverse web connecting the side walls.

14. In a cross-tie structure for connecting the front ends of locomotive side frame members, the combination of a front portion, a rear portion, both portions being adapted to tie together a pair of side frame members, and a portion for supporting a cylinder saddle, disposed intermediate the front and rear portions, the rear portion comprising a pair of spaced vertical parallel side walls each having vertical extensions affording increased area for attachment to side frame members, and a transverse web connecting the side walls.

15. In a cross-tie structure for connecting the front ends of locomotive side frame members, the combination of a portion for supporting a cylinder saddle, said portion comprising side walls and vertically spaced transverse webs connecting the side walls, and a rear portion projecting rearwardly of the saddle supporting portion, and comprising a pair of vertical side walls each having a vertical extension affording increased area for attachment to side frame members, and a transverse web connecting the side walls, said web having a depressed longitudinal portion, and an upstanding portion connecting the extensions.

16. In a cross-tie structure for connecting the front ends of locomotive side frame

members, the combination, in an integral casting, of a front section, a rear section, and an intermediate section for supporting a cylinder saddle, each section comprising a pair of vertical side walls, the side walls of the intermediate section being disposed inwardly of the side walls of one of the other sections, and vertically spaced transverse webs connecting the side walls of the intermediate section.

17. In a cross-tie structure for connecting the front ends of locomotive side frame members, the combination, in an integral casting, of a front portion comprising a pair of vertical side walls and vertically spaced transverse webs connecting the side walls, a rear portion comprising a pair of vertical side walls, and a single transverse web connecting its side walls, and a portion for supporting a cylinder saddle, disposed intermediate the front and rear portions, said intermediate portion having a pair of side walls disposed inwardly of the side walls of the front and rear sections, and vertically spaced transverse webs connecting its side walls.

18. In a cross-tie structure for connecting the front ends of locomotive side frame members, the combination, in an integral casting, of a front portion comprising a pair of vertical side walls and vertically spaced transverse webs connecting the side walls, a bumper bracket at the forward end of the front portion, a rear portion comprising a pair of vertical side walls and a transverse web connecting its side walls, and an intermediate portion for supporting a cylinder saddle, disposed intermediate the front and rear portions, and comprising a pair of vertical side walls disposed inwardly of the side walls of the front and rear sections, vertically spaced transverse webs connecting its side walls, a socket for a center pin stem, said socket having its walls connected to the webs, and ribs radiating from the walls of the socket and connected to the webs.
